(57) **CLAIM**

The ornamental design for a desk caddy, as shown and described.

DESCRIPTION

FIG. 1 is a perspective view of a desk caddy showing our new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a section view taken through the line indicated in FIG. 6 shown without the rest of the desk caddy for convenience of illustration;

FIG. 9 is a section view taken through the line indicated in FIG. 6 shown without the rest of the desk caddy for convenience of illustration; and,

FIG. 10 is a section view taken through the line indicated in FIG. 6 shown without the rest of the desk caddy for convenience of illustration.

The broken lines showing the broken away edges in FIGS. 8, 9, and 10 are included to show features that form no part of the claimed design.

1 Claim, 5 Drawing Sheets
